[57] CLAIM

A new and ornamental design for a combined lift attachment and hand implement, as shown and described.

DESCRIPTION

FIG. 1 is a perspective view of a combined lift attachment and hand implement showing my new design; FIG. 2 is an enlarged right side elevational view of the right side of FIG. 1, the left side being a mirror image thereof;

FIG. 3 is a top plan view of FIG. 2;

FIG. 4 is a bottom plan view of FIG. 2;

FIG. 5 is a front elevational view of FIG. 2; and

FIG. 6 is a rear elevational view of FIG. 2.

FIG. 1

FIG. 2

FIG. 3

FIG. 5

FIG. 4

FIG. 6
